UNITED STATES PATENT OFFICE.

THOMAS SHEHAN, OF CLEVELAND, OHIO.

SCREW-THREAD-CUTTING DEVICE.

1,391,514.

Specification of Letters Patent. Patented Sept. 20, 1921.

Application filed August 25, 1919. Serial No. 319,711.

To all whom it may concern:

Be it known that I, THOMAS SHEHAN, a citizen of the United States, residing at Cleveland, in the county of Cuyahoga and 5 State of Ohio, have invented a new and useful Screw-Thread-Cutting Device, of which the following is a specification.

This invention relates to improvements in devices for cutting screw-threads and more 10 especially to a device comprising a cutter-head which has a centrally located bore extending to the forward face of the cutter-head and is provided in its forward portion with radially arranged slideways which are 15 spaced circumferentially of said bore and engaged by slides carrying cutters for cutting screw-threads.

One object of this invention is to provide an improved application of the cutters 20 which are reversible end for end.

Another object is not only to removably secure each cutter to the slide carrying said cutter by a screw which is conveniently accessible, but to prevent any strain upon said 25 screw during operation of the cutter.

Another object is to permit exposure of the cutters and the cutter-carrying slides at the forward face of the cutter-head and to prevent displacement of said slides for- 30 wardly from the cutter-head.

Another object is to provide an improved operative connection between each cutter-carrying slide and the crank of a crank-shaft which has bearing in the cutter-head 35 and is employed in shifting or adjusting said slide radially of the cutter-head.

Another object is to render each cutter readily replaceable by another cutter.

With these objects in view, and to attain 40 any other object hereinafter appearing, this invention consists in certain features of construction, and combinations and relative arrangements of parts, hereinafter described in this specification, pointed out in the 45 claims, and illustrated in the accompanying drawings.

In said drawings, Figure 1 is a front end view of the forward end portion of a cutter-head embodying my invention. Fig. 2 is an 50 enlarged view of a portion of Fig. 1. Fig. 3 is a vertical section taken along the line 3—3, Fig. 2, looking in the direction indicated by the arrow. Fig. 4 is a horizontal section taken along the line 4—4, Fig. 2, 55 looking downwardly. Fig. 5 is a trans-

verse vertical section taken along the line 5—5, Fig. 3, looking in the direction indicated by the arrow. Fig. 6 is a longitudinal central section of a detached cutter-carrying slide.

Referring to said drawings, 10 indicates a cutter-head which (see Fig. 1) is provided at its forward face with slideways 12 which are arranged radially of the cutter-head and spaced equidistantly circumferentially of a bore 13 formed in any approved manner centrally and extending endwise of the cutter-head and to said face. Each slideway 12 is engaged by a slide 14 carrying a cutter 15 and extends from the bore 13 to the outer 70 circumferential surface of the cutter-head. Each slideway 12 has its rearward portion larger in width than the remainder of the slideway (see Fig. 4) so as to form two rearwardly facing shoulders 16 arranged at opposite sides respectively of the slideway, and the slide engaging said slideway has portions 17 thereof overlapping said shoulders. Obviously said shoulders and the shoulder-overlapping portions of said slide 80 prevent displacement of the slide forwardly from the cutter-head. Each slide 14 is of course shiftable endwise of the engaging slideway.

Each slide 14 (see Figs. 1, 2 and 3) is 85 shown provided, in its forward portion and centrally between its sides, with a recess 18 which is engaged by the cutter carried by said slide and extends longitudinally and from end to end of the slide and to the face 90 of the cutter-head, and said cutter extends endwise of the recess. The end portions of the recess 18 in each slide (see Fig. 6) extend, as at 19, to the rear side of the slide. Each cutter (see Figs. 4, 5 and 6) is provided at its rear side with a recess 20 which extends longitudinally of the cutter and is arranged centrally between and consequently spaced from the ends of the cutter, and said slide has a portion 21 occupying 100 and extending from end to end of said recess and forming a forwardly facing rear wall of said recess and also forming abutments for the longitudinal wall and end walls of said recess, as shown in Fig. 6. Each slide 105 14 is provided at its rear side (see Figs. 3, 4 and 6) with a slideway 22 arranged centrally between the ends and extending transversely of and through the slide. Each slide 14 has a screw-threaded hole 23 arranged 110

centrally between the end walls of the recess 20 in the cutter carried by said slide, and said hole extends rearwardly from the recess 18 in the slide to the slideway 22 in the slide and is arranged substantially at a right angle to the slideway 12 engaged by said slide. To facilitate the making of my improved screw-thread-cutting device each cutter is provided with a hole 24 which is arranged in line endwise and consequently registers with the hole 23 in the associated slide and extends to the forward side of the cutter and is enlarged in diameter, as at 25, at its forward end, and a screw has its shank 26 extending loosely through said hole 24 in said cutter and threaded into said slide at the aforesaid hole 23 in the slide. Said screw removably secures the associated cutter to the slide carrying the cutter and has its head 27 occupying the aforesaid enlarged end 25 of the hole 24 in said cutter. By the construction hereinbefore described it will be observed that each slideway 12 extends radially of the cutter-head at the forward face of the cutter-head and is engaged by a slide exposed at said face, that the cutter associated with said slide is secured to the slide by a screw having its head exposed at said face, and that said slide has a portion thereof arranged to form abutments for the walls of the recess in said cutter so that strain on said screw, during the operation of the cutter, is positively and inexpensively avoided.

I would also remark that each cutter has thread-cutting teeth 28 at each end and is reversible end for end, and it will be observed that said cutter, being secured to the associated slide by a screw having its head exposed at the forward face of the cutter-head, is readily detachable from the slide to reverse it end for end.

The slideway 22 in each slide 14 is arranged substantially at a right angle to the slideway 12 engaged by said slide. Said slideway 22 in each slide (see Figs. 2, 3 and 4) is engaged by a block 30 which is movable endwise of the slideway and provided with a central hole 31 which extends forwardly from the rear face of said block substantially at a right angle to the slideway 12 engaged by said slide, and a shaft 32, which has bearing in the cutter-head at the rear side of said slideway 22 in said slide and is substantially parallel with said hole, has a crank 33 loosely fitting said hole and forming a pivotal connection at one side of the axis of said shaft between the shaft and the aforesaid block. It will be observed therefore that the operative connection between a cutter 15 and the shaft 32 associated with said cutter comprises opposite side walls of the slideway 22 in the slide carrying said cutter and the block 30 which engages said slide-

way and embraces the crank 33 of said shaft, 65 and said block therefore forms a desirably large bearing between said crank and said slide. Obviously each slide 14, and consequently the cutter carried by said slide, are actuated endwise inwardly or outwardly 70 according as the associated crank-shaft 32 is rotated in the one or the other direction.

All of the shafts employed in the actuation of the cutter-carrying slides are preferably rotated simultaneously, but means for 75 simultaneously and correspondingly rotating shafts employed in readjusting or actuating cutters endwise, and means for locking said shafts in the desired adjustment of the cutters, are too well known in the art to 80 require description and illustration in this specification.

The cutters are shown in Fig. 1 as in position ready for operation on and externally of a piece of work (not shown) to be introduced between the inner ends of the cutters and to be operated on by the thread-cutting teeth on said ends of the cutters.

What I claim is:—

1. In a device for cutting screw-threads, 90 a cutter-head provided in its forward end portion with a slideway extending radially of the cutter-head, a cutter-carrying slide engaging said slideway and provided at its rear side with a slideway extending transversely of the slide substantially at a right angle to the first-mentioned slideway, a block movable endwise of the second-mentioned slideway and having a hole extending forwardly from the rear face of the 100 block substantially at a right angle to said second-mentioned slideway, and a shaft having bearing in the cutter-head at the rear side of the cutter-carrying slide and substantially parallel with said hole and provided with a crank which loosely fits said hole and forms a pivotal connection, at one side of the axis of said shaft, between the shaft and said block.

2. In a device for cutting screw-threads, 110 a cutter-head having a radially arranged slideway, a slide which engages said slideway and is provided at its rear side with a slideway extending transversely of the slide substantially at a right angle to the first-mentioned slideway and has a recess extending longitudinally of the slide forward of the second-mentioned slideway, a cutter engaging said recess, a screw securing the cutter to the slide, a block slideable endwise of the said second-mentioned slideway, and a shaft having bearing in the cutter-head at the rear side of the cutter-carrying slide and provided with a crank operatively connected with said block, the cutter having a recess 115 which is spaced from the ends and formed at the rear side and extends longitudinally of the cutter and has its end walls over-

lapped by the slide, said slide having a screw-threaded hole extending rearwardly from the first-mentioned recess to the aforesaid second-mentioned slideway, and the 5 aforesaid screw having its shank extending rearwardly from within the cutter and threaded into the slide at said threaded hole.

In testimony whereof, I sign the foregoing specification, in the presence of two witnesses.

THOMAS SHEHAN.
